Orwrey.

UNITED STATES PATENT OFFICE.

HARRY A. BARNES, OF MILWAUKEE, WISCONSIN, ASSIGNOR TO PREMIER MANUFACTURING COMPANY, OF HARTFORD, CONNECTICUT.

DESIGN FOR A LOWER MEMBER OF FIFTH-WHEELS.

SPECIFICATION forming part of Design No. 35,037, dated September 3, 1901.

Application filed April 13, 1900. Serial No. 12,777. Term of patent 14 years.

To all whom it may concern:

Be it known that I, HARRY A. BARNES, a citizen of the United States, residing at Milwaukee, in the county of Milwaukee and State 5 of Wisconsin, have invented and produced a new and original Design for the Lower Member of Fifth-Wheels, of which the following is a specification, reference being had to the accompanying drawings, forming a part 6 thereof.

Figure 1 is an inverted plan view of the lower member of a fifth-wheel, showing my new design. Fig. 2 is a rear elevation, Fig. 3 is a plan view, and Fig. 4 is a sectional 5 view, of the same on the line 4-4, Fig. 3.

As shown in the drawings, the leading or material features of my design consist of a circular plate A, having a plain upper surface with a central circular recess B, as shown in Figs. 3 and 4, and a central cross-bar C on

the under side with an aperture c between it and the plate; as shown in Figs. 2 and 4. The plate has a marginal flange D on the under side, and this flange is broken or partially cut away on the rear side, forming a 25 segmental recess E. The plate A is also formed with a circumferential groove F in its periphery.

Having thus described my invention, what I claim as new, and desire to secure by Letters 30 Patent, is—

The design for the lower member of a fifth-wheel as herein shown and described.

In witness whereof I hereto affix my signature in presence of two witnesses.

HARRY A. BARNES.
